UNITED STATES PATENT OFFICE.

WILLIAM SUTTON, OF TABLEROCK, NEBRASKA.

KILN.

SPECIFICATION forming part of Letters Patent No. 760,821, dated May 24, 1904.

Application filed June 6, 1903. Serial No. 160,410. (No model.)

To all whom it may concern:

Be it known that I, WILLIAM SUTTON, a citizen of the United States, residing at Tablerock, in the county of Pawnee and State of Nebraska, 5 have invented new and useful Improvements in Kilns, of which the following is a specification.

This invention relates to kilns, the object of the invention being to provide a continuous or 10 progressive kiln embodying a circular series or succession of burning-chambers, gas-generators, and furnaces so connected up and placed in communication that the burning chambers or compartments may be successively charged 15 with brick, lime, cement, or other clay products and the latter properly treated and removed from their respective compartments and chambers without interrupting the operation of the kiln as a whole.

20 A further object of the invention is to provide a special arrangement of burning chamber or compartment in connection with a suitable stack or draft-flue whereby the necessary draft is obtained without the necessity of 25 employing a high stack.

Another object of the invention is to combine with the burning chambers or compartments a specially-arranged furnace or gas-producing generator with gas-ports located in 30 such manner as to enable either up or down draft to be obtained.

Another object is to so arrange the furnace or coking-chamber that the same may be supplied with fuel either from a suitable magazine above or a door leading through the outer 35 wall of the structure.

A further object of the present invention is to combine with the burning chambers or compartments and gas-generators a hot-air tunnel 40 so arranged with respect to the furnace as to convey the hot air between and supply the same to one or a group of burning-chambers, thus adapting the waste heat radiating from the brick already burned to be utilized for the 45 purpose of water-smoking or advance warming the green brick or other articles placed in the burning - compartments. The arrangement referred to also enables the coke-burning magazine to be supplied with hot air, which 50 will assist combustion.

With the above and other objects in view the invention consists in the novel construction, combination, and arrangement of parts, as hereinafter fully described, illustrated, and claimed.

55

In the accompanying drawings, Figure 1 is a horizontal section through a kiln constructed in accordance with the present invention. Fig. 2 is a central vertical section through the same, taken in line with the doorways leading 60 to the burning-chambers. Fig. 3 is an enlarged radial section through one of the burning-chambers, showing the gas-generator, coke-burning magazine, hot-air tunnel, draft-deflecting wall, steam-vents, magazine, draft- 65 flues, &c.

Like reference-numerals designate corresponding parts in all the figures of the drawings.

The kiln contemplated in this invention is 70 substantially circular in its general plan or in the form of a vertical cylindrical structure and comprises, essentially, outer and inner walls, between which is arranged a circular series of burning chambers or compartments 75 1 to 15, inclusive, as shown in Fig. 1. Each of said chambers or compartments is in the form of the segment of a circle, the compartments being divided from each other by means of temporary partitions 16, composed by preference of paper or pasteboard, whereby they may readily be destroyed either by hand or by the fire, and thus removed in order to allow the heat or products of combustion to pass from one chamber to another. The burning 80 chambers or compartments 1 2 3, &c., are comprised between the outer wall 17 and the inner wall 18 of the structure, and access is had to the burning-chambers through suitable doorways 19, which extend through the outer 85 wall 17, while between each pair of adjoining doorways 19 are arranged one or more fuel-openings 20, by means of which the fuel may be fed to the gas-generator, hereinafter described. The outer and inner walls are connected by means of a top wall 21, which is sprung over the circular series of chambers 1, 2, and 3 in the form of an arch, as shown in Figs. 2 and 3. Centrally of the structure is arranged a stack 22 of suitable size, while 90 95 100

encircling the stack is what I term an "inner" cleaning-tunnel 23, the floor 24 of which is arranged above the bottom of the stack and also above the floor of the series of radial passages 25, which lead directly into the stack 22, as shown in Fig. 2. Any desired number of doorways controlled by suitable doors may be formed through the inner wall 18 for the purpose of allowing an attendant to pass into and out of the tunnel 23 for the purpose of 10 cleaning the base of the stack and carrying out the material which has accumulated therein.

Adjacent to each fuel-cleaning door and arranged below the plane thereof is a coke-burning table 26, as shown in Fig. 3, while immediately above the table is a fuel-magazine in the form of a vertical opening extending from the top or roof of the structure downward, so as to deposit the fuel directly on the table 26, 20 which forms the burning-floor of the furnace, where the fuel is coked, the fuel also being coked as it passes over the outer edge 28 of the table and falls downward through a vertically-extending magazine 29 to the ash-pit 30 below. 25 Extending immediately over the coking-table and running in a direction substantially radial to the stack is a gas-generating chamber 31, which forms an extension of the doorway 20 and leads directly into the adjacent burning-chamber. At the other side of the table is a vertical draft-passage 32, between which and the burning-chamber is an interposed wall 33, which terminates above the floor 34 of the burning-chamber and also beneath the roof or upper 35 wall of the gas-generating chamber 31. By means of suitable doors or dampers the passage 35, which forms the upper gas-port, may be thrown open and closed, and in a similar manner the passage 36, which forms the lower gas-port, may be thrown open or closed, thus enabling a downdraft or an updraft to be produced within the burning-chamber, the draft being also regulated and controlled by means of a series of steam-vents 37, extending from 40 the arched top of the burning-chamber upward through the top or roof of the structure, as shown in Fig. 3, said steam-vents being designed to be controlled by doors or dampers.

Extending in a circle around the kiln and 50 beneath the burning-floor of the coking-table is a hot-air tunnel or conduit 38, which is placed in communication with each of the burning-chambers or compartments 1, 2, 3, &c., by means of a passage 39, as shown in Fig. 3. In connection with the hot-air tunnel 38 a series of doors or dampers may be employed for shutting off communication between said tunnel and any of the burning-chambers 1 during the cooling operation of the brick or other 55 products contained in the burning-chambers. A passage 40 extends from the ash-pit 30 outward, so as to enable the ashes to be removed through a suitable door controlling the outer end of said passage in a manner which will 60 readily be understood.

Short draft-flues 41 extend beneath the inner wall 18 of the kiln and afford communication between the burning-chambers and the stack, while the other draft-flues 42 extend from openings 43 in the floor of each burning-chamber and near the outer side of the burning-chamber beneath the floor of such chamber and open out into the passages 25, which lead from the inner cleaning-tunnel 23 into the stack 22. The draft-flues 41 and 42 are 70 75 designed to be controlled by suitable dampers.

In the operation of the kiln suppose that fifteen separate burning chambers or compartments are employed, the same being divided from each other by the temporary paper or 80 pasteboard partitions 16, the opposite edges of which may be inserted in grooves in the kiln-walls or connected therewith in any convenient manner. We will assume that all of the burning-chambers with the exception of 85 1 and 2 are full of burned brick or brick in the process of burning. Chamber 1 is being filled, and chamber 2 is being emptied, the brick in chambers 3, 4, 5, 6, and 7 having been burned and being now in the process of cooling and the brick in chambers 8, 9, and 10 being fired. The draft-flues leading from 90 chambers 11, 12, 13, 14, and 15 to the stack are open, while all the other draft-flues leading to the stack are closed. All the outside 95 doors controlling the passages 20 to the gas-generators are closed except those leading to chambers 1, 2, and 4. Chamber 15 is then closed by two temporary partitions. Cold air is admitted to chamber 4 and drawn back 100 through chamber 3 to the hot-air tunnel 38 to chamber 15, in which the bricks are being dried or water-smoked, and forward through chambers 5, 6, and 7, and thereby heated to a 105 burning temperature to nourish the fires and generate gas in chambers 8, 9, 10, 11, 12, 13, and 14, which are being fired and slowly warmed in advance. In this way waste heat 110 radiating from the burned and cooling bricks is utilized to raise the temperature in chambers 8, 9, and 10, which are being filled. When using the doors controlling the fuel-openings 115 20, hot air is passed under the doorways through the tunnel 38, the passage being regulated by dampers. When chamber 1 is filled, it is inclosed between temporary partitions, and the drying, burning and cooling, emptying and filling are all advanced one chamber or compartment at a time, thus making the 120 work practically continuous.

It will be observed that by means of the arrangement of tunnels and air-passages hereinabove described the necessary oxygen and hot air are supplied to the coke-burning furnace to assist in and effect a thorough combustion of the coal; also, that by being able to place the burning-chambers in communication with any one or more of the remaining chambers I am able to utilize the waste heat radiating from the bricks already burned and use 125 130

said heat for the purpose of water-smoking or advance warming the green bricks. By means of the deflecting-wall 33 the gas may be fed to the furnace either at a high or low point and 5 either up or down draft obtained. When the passage below the deflecting-wall is closed, the heat and gases will enter the burning-chamber over the top of said deflecting-wall and pass downward and out through the draft-flues 41 to the stack. If the passage at the top of the wall is closed and the bottom opened, the stack draft-flues are shut off, and the caps or dampers of the steam-vents 37 open, an upward draft is obtained. Either the vertical 10 magazine 27 or the fuel-door opening 20 may be used for supplying fuel to the burning floor or table 26. When the magazine is filled with fuel, the coking-table will be necessarily partly filled, and when the draft is turned on 15 the heat and products of combustion will be drawn through the coking-chamber, the gas passing into the burning-chamber, where it is consumed. The coke is then raked into the coke-burning magazine, where it is consumed, 20 the heat passing into the burning-chamber. As the coke is removed from the table or burning-floor it is automatically replaced by the coal from the magazine above.

One of the chief advantages of the present 30 invention resides in the fact that by means of the system of tunnels the heat which would otherwise be wasted may as it radiates from the burning and cooling brick be conveyed to other chambers or compartments in which the 35 green brick has been placed, and in this way the green brick may be warmed and partially dried in advance before the products of combustion from the gas-generators and coking-tables are admitted directly thereto.

40 Having thus described the invention, what I claim as new is—

1. A kiln comprising a stack, burning-chambers or compartments arranged in a series around the stack and having flue means connecting the same, draft-flues leading from the 45 burning-chambers to the stack, gas-generating furnaces located between the doorways, and means for directing the products of combustion into the burning-chambers either near the floor or at a point remote from the floor 50 of the burning-chambers.

2. A kiln comprising a stack, burning-chambers arranged in a series around the stack, draft-flues leading from the burning-chambers 55 to the stack, gas-generating furnaces located between the doorways leading to the burning-chambers, a hot-air tunnel encircling the kiln outside of the burning-chambers and communicating with the furnaces, and means for directing the products of combustion into the 60 burning-chambers either near the floor or at a point remote from the floor of the burning-chambers, substantially as described.

3. A kiln comprising a centrally-arranged 65 stack, burning-chambers or compartments ar-

ranged in a circular series around the stack and having flue-connecting means, draft-flues leading from the bases of the burning-chambers to the stack, doorways leading through the outer wall of the kiln to the burning-chambers, gas-generating furnaces located between the doorways, and means for directing the products of combustion into the burning-chambers either near the floor or at a point remote from the floor of the burning-chambers, substantially as described. 70 75

4. A kiln comprising a centrally-arranged stack, burning-chambers or compartments arranged in a circular series around the stack, draft-flues connecting the bases of the burning-chambers with the stack, vent-openings leading upward and outward through the roof of the burning-chambers, doorways leading to the burning-chambers through the outer wall of the kiln, a coke-burning furnace arranged between adjacent doorways, a hot-air tunnel encircling the kiln outside of the burning-chambers, a passage-way leading between the furnace and hot-air tunnel, and a passage-way for conveying the hot air and products 80 of combustion from the furnace into the adjacent burning-chamber, substantially as described. 85 90

5. A kiln comprising a centrally-arranged stack, burning-chambers arranged in a circular series around the stack, draft-flues connecting the burning-chambers and stack, doorways leading to the burning-chambers, furnaces arranged between adjacent doorways, a hot-air tunnel extending around the outside 95 of the burning-chambers, a coke-burning magazine leading from the furnace to the hot-air tunnel, a fuel-magazine leading through the upper portion of the kiln and arranged to discharge on the burning-floor of the furnace, one or more passages for conveying the products of combustion and hot air into the adjacent burning-chamber, and a deflecting-wall for diverting the products of combustion prior to their entrance to the burning-chamber. 100 105 110

6. A kiln comprising a centrally-arranged stack, burning-chambers or compartments arranged in a circular series around the stack, draft-flues affording communication between said burning-chambers and the stack, a hot-air tunnel encircling the burning-chambers in a plane approximately on the level of the bottoms of the burning-chambers, gas-generating furnaces for supplying gas to the burning-chambers and heat to the tunnel, and substantially horizontal passages leading from the hot-air tunnel to the different burning-chambers or compartments, substantially as described. 115 120 125

In testimony whereof I affix my signature in presence of two witnesses.
